(57) **CLAIM**

The ornamental design for a graphics card, as shown and described.

DESCRIPTION

FIG. 1 is a front, top, left side perspective view of a graphics card, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The equal-length broken lines in the drawings depict portions of the graphics card that form no part of the claimed design. The dash-dot-dash lines define the boundaries of the claim.

1 Claim, 7 Drawing Sheets
